A. ZAWADA,

DROP HAMMER,

APPLICATION FILED JUNE 18, 1919.

1,337,379.

Patented Apr. 20, 1920.

Inventor

Alex Zawada

My law Attorney

Frank Ledermann

UNITED STATES PATENT OFFICE.

ALEX ZAWADA, OF REMBRANDT, MANITOBA, CANADA.

DROP-HAMMER.

1,337,379.

Specification of Letters Patent. Patented Apr. 20, 1920.

Application filed June 18, 1919. Serial No. 305,046.

To all whom it may concern:

Be it known that I, ALEX ZAWADA, a citizen of Ruthenia, residing at Rembrandt, Province of Manitoba, Dominion of Canada, have invented certain new and useful improvements in Drop-Hammers, of which the following is a specification.

This invention has for its object the provision of a drop hammer adapted to be 10 pedally operated and in which the tup or hammer element is adjustable in a novel manner with relation to the anvil or die block.

This and other objects are attained by the 15 novel construction and combination of parts hereinafter described and shown in the accompanying drawings, forming a material part of this disclosure, and in which—

Figure 1 is a vertical sectional view taken 20 through a hammer made in accordance with the invention.

Fig. 2 is a top plan view thereof, and

Fig. 3 is a perspective view showing the 25 sliding tup or hammer element.

Referring to the drawings in detail, the 30 numeral 10 indicates the base of the hammer from which rises a column 11, having an extending vertical guide portion 12, at its front side, the same being in alinement 35 with an undercut transverse recess 14, formed in the anvil element 15, immediately above the base and which contains a slide 16 carrying a die 17.

Mounted to turn freely on a pin 18, set in 35 a recess 19, in the lower portion of the base, is a lever 20, having a curved forward projecting portion 21 adapted to receive the foot of the operator, the lever having upon 40 its upper surface a lug 22, in which is secured the lower end of a cable 23, passing over a guide pulley 24, mounted upon a pin 25, set transversely in an open recess 26, formed in the upright 11, and from which 45 extends an opening 27 containing the cable 23, the upper end of the cable being secured to the rim of a pulley 28, mounted on a spindle 29, passing transversely through the 50 opening 27 at the top of the column 11.

Also secured upon the spindle 29 is an 55 other, larger sheave pulley 30, to the rim of which is attached one end of the heavier cable 31, engaged at its lower end in a rectangular bar 32 slidably engaged in an elongated opening formed centrally in the 60 upper end of a sliding tup 33, having longitudinal V-shaped elements 34 upon its op-

posite sides suited to be received in V-shaped grooves 35, formed in the front portion 12 of the column, the same being machined so that the slides of the tup 34 60 will move freely therein.

Formed transversely through the bar 32 are a plurality of rectangular openings 36, receptive of a square pin 37, passing through the tup 33 near its upper end and at right 65 angles to the slide elements 34. This square pin passes outward through a slot 37', formed in the column 12, whereby it is provided with an operating head 38 by which it may be withdrawn.

In order to hold the square pin 37 against 70 accidental displacement, a flat spring 39 is held by rivets 40 to the tup 33, and is arranged to exert frictional pressure against the extending lower surface of the pin 37, 75 whereby it is held in any desired adjustment.

Extending downward from the tup is a 80 usual form of punch holder 41, provided with a screw 42, for securing the punches 80 therein.

In operation, the parts having been assembled in the position as indicated, and the operator accustomed to a certain movement of the treadle or lever 21 in operating 85 the hammer, should it be desired to exert a relatively light blow, the square bar 32 is adjusted so that the movement transmitted through the lever and cable actuates the tup a relative small amount only, while 90 on the contrary, if it be desired to deliver a heavier blow, the bar 32 is inserted to a greater length within the tup so that the latter is caused to move through a greater range of action upon an equivalent move- 95 ment of the lever 21.

Having thus described my invention what I claim as new and desire to secure by Letters Patent, is—

1. In a drop hammer, the combination 100 with the frame thereof, a tread lever pivoted in the lower portion of said frame, a cable connected therewith, a spindle mounted transversely to said frame at the upper end thereof, pulleys engaged on said spindle, 105 said cable being secured to one of said pulleys, another cable engaged with the other of said pulleys, a tup slidably mounted in said frame, said cable being engaged with said tup, of means for adjusting the movement communicated to said tup by said 110 pedal lever.

2. In a drop hammer, the combination with a base, a column rising therefrom, and a pair of pulleys journaled in the upper portion of said column, of a foot lever journaled in said base, flexible connections between said foot lever and one of said pulleys, a tup slideable in said column, said tup having a rectangular axial opening in the upper end, a bar slidably engaged in the opening of said tup, means for adjusting said bar within said tup, and flexible connections between said bar and the other pulley.
3. In a drop hammer, the combination with a frame, a spindle in said frame, pul-

leys engaged on said spindle, a treadle and a tup slidably arranged therein, of a bar adapted to slide in said tup, said bar having transverse openings, a pin passing through said tup and openings into said bar where-
by tup and bar may be relatively adjusted, a flat spring riveted to said tup for frictionally holding said tup in an adjusted position and operative connections between said bar and pulleys, substantially as described and for the purpose set forth.

In testimony whereof I have affixed my signature.

ALEX. ZAWADA.
